THE STAY

Charles Earl Brooks, Oakland, Calif.

Application June 24, 1935, Serial No. 28,156

4 Claims. (Cl. 24—57)

This invention relates to mechanical devices used with neckties to prevent displacement of the knot thereof once it is positioned, by the wearer, with respect to his collar.

5 It is a principal object of the invention to provide a device which will maintain the knot of a four-in-hand tie in correct position relative to the collar regardless of how loose the knot, or the neck encircling portion of the tie, may become. 10 Other objects of the invention are to provide a device of the character described which is of minimum size and readily concealed by the knot of the tie; to provide such a device possessed of the utmost of simplicity in structure and method of 15 attachment; to provide a device of the character described in which manufacturing costs are reduced to an absolute minimum, and to provide a tie stay which may be adjusted to fit knots of various sizes.

20 Referring to the drawing:

Figure 1 is a front elevation of one form of the tie stay of this invention.

Figure 2 is a side elevation of the device shown in Figure 1.

25 Figure 3 is a front elevation of a modified form of tie stay.

Figure 4 is a side elevation of the device illustrated in Figure 3.

Figure 5 is a perspective view showing the mode 30 of attachment of the tie stay of Figure 1 to a collar and tie.

Figure 6 is a front elevation of the adjustable form of tie stay.

Figure 7 is a side elevation of the device of 35 Figure 6.

In detail, Figure 1 illustrates one form of the invention in which a length of hard drawn or spring wire is doubled upon itself to simulate a hair pin provided with an open loop 6 at the bend 40 thereof, and spaced free ends having upwardly bent portions 8 to provide a pair of hooks 9. Each of the sections of the wire lying between the loop 6 and the hooks 9 is provided with a short portion 10 which is directed slightly inwardly to 45 provide a restricted opening 11 for the loop, and the remainder 12 of each section is reentrantly bent at the point 13 to provide an opening 14, of relatively large size, in communication with the opening 11.

50 In the transverse vertical plane, as shown in Figure 2, the portions 10 and the upwardly directed portions 8 of the hooks 9 are disposed in offset parallel relationship, with the connecting portions 12 disposed in angular relationship there- 55 with.

Figure 5 illustrates the method of applying the stay. After the knot 15 of the tie 16 has been formed by the wearer, and placed in the desired position with respect to the collar 17, the knot is lifted to expose the collar button 18. The stay 5 is then placed over the collar button so that the head and shank of the latter enter the opening 14 whereupon the stay is pulled downwardly to cause the shank to enter the loop 6. The opening 11 of the loop is purposely made narrower 10 than the diameter of the shank so as to prevent ready displacement of the latter from the loop upon upward movement of the stay, there being, of course, sufficient resiliency in the portions 10 to permit the width of the opening to increase as 15 the shank passes therethrough. With the stay in position on the collar button, as just described, the wearer next engages the hooks 9 with the lower edge 19 of one of the loops forming the knot of the tie which will maintain the knot in its 20 correct position with respect to the collar.

In Figures 3 and 4 is shown a modified form of construction for the stay. In this case the stay is made of sheet metal stamped to provide an enlarged end 20 provided with a notch 21 cor- 25 responding to the loop 6, and an aperture 22, communicating with the notch 21, which corresponds with the opening 14 to clear the head of the collar button. A shank 23 is provided having an upturned portion 24 at the lower end to 30 provide a hook 25 similar to the hooks 9 of the other form of the invention. The angular bends of the two modifications, when viewed in the transverse vertical plane, are identical.

In Figures 6 and 7 is illustrated another form of 35 the invention wherein adjustment has been provided so that the stay may be regulated to support ties having varying sizes of knots, or to vary the pressure on the knot to maintain it in intimate contact with the collar. In this modifica- 40 tion the length of wire is doubled to provide the loop 6 at the bend 7, similar to the device of Figure 1, and the portions 10 are converged, as before, to provide the restricted opening 11 for the loop. The right hand extension 26, of the 45 portion 10, is provided with an outwardly curved reentrant bend which terminates at the point 27 in a straight shank portion 28. The opposite extension 29 is bent similarly to the portion 26 but terminates adjacent the shank at the point 28, 50 and the two curved portions thus form the opening 14.

Slidably mounted on the shank 28 is a sleeve 55, which will be recognized as the familiar safety device commonly used with scarf pins to

prevent separation thereof from ties, and the sleeve has secured thereto a short piece of wire 31 directed upwardly to provide a hook similar to the hooks 9 and 25 of the other modifications. 5 Since the sleeve 30 is free to move only in an upward direction, with relation to the shank 28, it will be seen that the position of the hook may be adjusted upwardly, with respect to the center of the loop 6 which is the position of the collar 10 button of the wearer, so that regardless of the size of the knot of the tie the hook will firmly engage therewith, or the upward pressure of the hook on the knot to urge it into intimate contact with the collar may be varied. The sleeve, as is 15 well known, may be released by grasping the ball end of the plunger 32, with the finger tips, and drawing downwardly thereon whereupon the engagement of the frictional mechanism with the shank within the sleeve will be released to permit 20 withdrawal of the sleeve from the shank.

From the foregoing description it will be seen that a stay has been provided which will overcome the difficulty of maintaining the knot of a tie always in correct position with respect to the 25 collar. Heretofore this has been practically impossible due to the downward pull exerted on the tie caused by the frictional engagement of the tie with the wearer's vest and shirt during movement of his body. The necessity of having to readjust one's tie at frequent intervals is obviously very annoying.

The tie stay of this invention overcomes this difficulty by supporting the knot of the tie from the collar button where it cannot be displaced

regardless of the downward pull exerted on the tie.

What I claim is:

1. A tie stay for preventing displacement of the knot of a tie with respect to a collar secured to a wearer by means of a collar button, comprising a member secured to said collar button, and means for engaging said tie connected with said member and adjustable relative thereto. 5

2. A tie stay for preventing displacement of the knot of a tie with respect to a collar secured to a wearer by means of a collar button, comprising a member secured to said collar button, and means for engaging said tie slidably connected with said member and adjustable relative 15 thereto.

3. A tie stay for preventing displacement of the knot of a tie with respect to a collar secured to a wearer by means of a collar button, comprising a member secured to said collar button, and means 20 for engaging said tie connected with said member for movement freely in one direction relative thereto.

4. A tie stay for preventing displacement of the knot of a tie with respect to a collar secured to a 25 wearer by means of a collar button, comprising a length of wire having a straight shank portion and a portion bent to provide a loop for engaging said collar button, and a sleeve freely slidable in one direction on said shank and having a projection thereon for engaging a portion of said tie.

CHARLES EARL BROOKS.
